UNITED STATES PATENT OFFICE

HARRY SEBELL, OF BOSTON, MASSACHUSETTS, ASSIGNOR OF ONE-HALF TO ARTHUR H. PARKER, OF LEXINGTON, MASSACHUSETTS

MEASURING PUMP

Application filed June 4, 1929. Serial No. 368,248.

This invention relates to measuring pumps and particularly to a measuring pump of the type shown in my co-pending application Serial No. 339,465, filed January 2, 1929. The pump illustrated in said application comprises a cylinder of known capacity and having a port, an inlet pipe and a discharge pipe with which the cylinder port is adapted to communicate alternately, a piston operating in said cylinder and means to prevent any movement of the piston except that of the suction stroke while the cylinder is in communication with the inlet pipe, and any movement of the piston except that of the discharge stroke while the cylinder is in communication with the discharge port.

One object of the present invention is to improve a measuring pump of the above type by providing novel means for actuating the piston to give it the suction and discharge strokes and also to actuate the cylinder between the strokes to shift its position in order to bring its port into communication with the discharge pipe at the proper times in the cycle of operations.

In my present invention I provide a novel actuating device which is common to both the piston and the cylinder and by which the piston and cylinder are given their respective movements in proper timed relation.

In order to give an understanding of the invention I have illustrated in the drawings a selected embodiment thereof which will now be described after which the novel features will be pointed out in the appended claims.

Fig. 1 is a front view of a measuring pump embodying my invention with a part broken out;

Fig. 2 is a top plan view also with a part broken out;

Fig. 3 is a section on the line 3—3, Fig. 4 showing the position of the actuating pinion during the discharge stroke;

Fig. 4 is a vertical section on substantially the line 4—4, Fig. 1;

Fig. 5 is a section similar to Fig. 3 but showing the position of the parts during the suction stroke;

Fig. 6 is a fragmentary view of the rack and pinion structure;

Fig. 7 is a fragmentary view illustrating the operation of the pinion 12 and rack 10.

The main elements of the pump herein shown are similar to those found in my above-mentioned co-pending application Serial No. 339,465. These comprise a cylinder member 1 having a known capacity and which is enclosed in a stationary housing 2. This housing 2 has an inlet pipe 3 leading thereto and a discharge pipe 4 leading therefrom. The cylinder 1 is provided with a port 5 and said cylinder is turnable in the casing 2 to put the port 5 into communication with either the inlet pipe 3 or the discharge pipe 4.

6 indicates a piston operating in the cylinder. By placing the cylinder with its port 5 in communication with the inlet pipe 3 as shown in Fig. 5 during the up or suction stroke of the piston 6, the cylinder will be filled with a measured quantity of liquid and then by shifting the cylinder to bring its port 5 into communication with the discharge pipe 4 and forcing the piston downwardly this measured quantity of liquid will be discharged. The operation of the device, therefore, involves not only giving the piston its reciprocating movement but also involves turning the cylinder at the proper times to bring its port 5 into communication alternately with the inlet pipe 3 and discharge pipe 4.

My invention relates to a novel means for thus actuating both the piston and the cylinder. I have provided a common actuator with suitable connections so that when the actuator is operated the piston will be reciprocated and the cylinder will be turned in proper timed relation, the turning of the cylinder from one position to another occurring at the end of the piston stroke and while the piston is at rest.

The piston is shown as having a piston rod 7 connected thereto which is secured to a cross head 8. The cross head 8 has rigidly secured to it a depending actuating bar 9 which is located on the outside of the casing 2 and which has secured to its lower end a rectangular skeleton rack bar member 10 with the rack teeth 11 on the outer face thereof. This rack bar co-operates with an operating

pinion 12 which is shown as fast on a shaft 13 journalled in a bearing 14 formed on a supporting bridge member 15 that is rigid with the casing.

5 The shaft 13 is shown as provided with a handle 16 by which the pinion 12 may be rotated. The rack teeth 11 are held in engagement with the pinion 12 by means of a keeper member 17 which is loosely mounted on the 10 shaft 13 between the pinion 12 and the bearing 14 and which is provided with a retainer portion 18 that engages the inner face 19 of the skeleton rack member 10.

Figs. 1, 4 and 6 show the position of the 15 rack bar relative to the pinion when the piston is at the upper end of the stroke and while the cylinder is being turned from the position shown in Fig. 5 to that shown in Fig. 3, the position of the piston 6 corresponding to a 20 mid position of the cylinder.

Assuming that the cylinder is being rotated in the direction of the arrow Fig. 6 it will be seen that the rack bar will be moving horizontally toward the left as indicated by 25 the arrow. The rack bar is rigid with the actuator bar 9 and the latter is so connected to the cylinder that the lateral or horizontal movement of the rack bar gives a turning movement to the cylinder. The cylinder 30 head 20 is provided with a plate 21 which is formed with a notch 22 in which the actuator bar 9 operates and hence any lateral movement of the rack bar and the actuator member 9 will operate through the plate 21 and 35 cylinder head 20 to turn the cylinder.

The rack bar has been so designed that the extent of its horizontal movement is just sufficient to shift the cylinder from the position shown in Fig. 5 to that shown in Fig. 3 or vice 40 versa.

Referring again to Fig. 6 when, due to the rotation of the pinion 12, the rack bar member 10 has been carried to the left to a point where the pinion reaches the corner 23 of 45 the rack bar then the retainer 18 will enter the pocket 24 formed in the inner face of the rack bar member as seen in Fig. 7 and as the rotation of the pinion 12 continues said pinion will travel around the corner of the 50 rack bar or, in other words, the rack bar will begin to descend on the left hand side of the pinion, the engagement of the keeper 18 with the inner face 19 of the rack bar maintaining the proper engagement of the teeth of the 55 pinion with the rack bar teeth. As the pinion rounds the corner of the rack bar member the keeper 17 will swing into the horizontal position shown in Fig. 5 and as the pinion 12 continues its rotation the teeth on the right 60 hand side of the rack bar will be in engagement with the pinion and the rack bar will be moved downwardly thus giving the piston its downward or discharge stroke. At this time the cylinder port is in communication with 65 the discharge pipe 4 as shown in Fig. 3.

When the rack bar has reached the downward limit of its movement the keeper 18 will enter the pocket 25 and the rack bar will begin its swing to the right underneath the pinion.

70 While the upper portion 26 of the rack bar is passing under the pinion the piston will be stationary but the cylinder will be turned from the position shown in Fig. 3 to that shown in Fig. 5 thus bringing the cylinder port 5 into communication with the inlet pipe 3. When the upper side of the rack bar has travelled across underneath the pinion 12 then the co-operation of the keeper with the rack bar will cause the rack bar to move upwardly on the right hand side of the pinion thereby giving the piston its suction stroke. At this time the cylinder port 5 is in communication with the inlet pipe 3 so that the cylinder will be filled with liquid.

80 When the piston reaches the upper end of its stroke the rack bar will pass over above the pinion as shown in Fig. 6 and while the piston remains stationary at the upper end of the stroke the cylinder will be shifted from the position shown in Fig. 5 to that shown in Fig. 3. By simply turning the crank handle 16 therefore the piston will be given its alternate suction and discharge strokes and the cylinder will also be shifted from a position 85 with its port 5 in communication with the inlet port 3 as shown in Fig. 5 to a position with its port 5 in communication with the discharge pipe 4 as shown in Fig. 3, while the piston remains stationary at the upper end of the 90 stroke, and will be given its reverse movement back into the position shown in Fig. 5 while the piston is stationary at the lower end of the 95 stroke.

100 Means are provided to prevent the crank 105 from being turned backwardly thus compelling always a forward movement of the pinion. For this purpose the shaft 13 has rigid thereon a ratchet wheel 27 with which co-operates a spring pawl 28 pivoted at 29 to the 110 bridge member 15. The pawl allows the ratchet wheel to rotate in the direction of the arrow but prevents backward rotation.

115 Under some circumstances it may be desirable to discharge a measured quantity of liquid from the cylinder 1 which is less than the full capacity of said cylinder. In order to permit this to be done I have provided a gauge member 30 which is adjustably secured to the cross head 1 and which will by its engagement with the cylinder head limit the 120 downward movement of the piston.

125 If it is desired to discharge the entire contents of the cylinder then the gauge 30 will be raised to a point where it will not engage the cylinder head even when the piston is at the bottom of its stroke. On the other hand, if it is desired to discharge only one-half the contents of the cylinder or some other proportional part thereof then the gauge 30 will 130

be correspondingly adjusted on the cross head, the adjustment being such that it will engage the cylinder head during the downward movement of the piston at the time that the desired quantity of liquid has been discharged. As herein shown the cross head 8 is provided with a guideway 31 in which the gauge bar 30 slides, the latter being held in adjusted position by a set screw 32 which has 10 a pointed end adapted to be received in any one of a number of recesses 33 with which the gauge bar is provided.

The bridge member 15 is secured to the casing 2 through the medium of spacer members 15 40 and these members are preferably so placed that when the rack 10 is moving vertically it will engage with one or the other of said spacer members as shown in Figs. 3 and 5.

20 The cylinder head 20 is shown as rigidly secured to the cylinder 1 through the medium of a screw 35. Said cylinder head is provided with the flange 37 which fits inside the cylinder and the screw 35 extends through 25 the upper end of the cylinder and into the flange. This screw also operates in a slot 34 formed in the casing 2 and thus serves to retain the cylinder in the casing.

While I have illustrated a selected embodiment of my invention I do not wish to be limited to the constructional features shown.

I claim.

1. In a measuring pump, the combination with a cylinder having a port, an inlet pipe, 35 a discharge pipe, said cylinder being movable from a position in which its port communicates with one of said pipes to a position in which its port communicates with the other of said pipes, a piston operating in and fitting the bore of said cylinder, and means operating both to reciprocate the piston and to move the cylinder from one position to the other.

2. In a measuring pump, the combination 45 with a cylinder having a port, of an inlet pipe, a discharge pipe, said cylinder being turnable about its axis from a position in which its port registers with the inlet pipe to a position in which its port registers with the 50 discharge pipe, a piston operating in and fitting the bore of said cylinder, and means operating both to reciprocate the piston and to turn the cylinder from one position to the other.

55 3. In a measuring pump, the combination with a cylinder having a port, of an inlet pipe, a discharge pipe, said cylinder being movable from a position in which its port communicates with one pipe to a position in 60 which its port communicates with the other pipe, a piston operating in and fitting the bore of said cylinder, means common to the piston and the cylinder to reciprocate the piston and to move the cylinder from one position to the other.

4. In a measuring pump, the combination with a cylinder having a port, of an inlet pipe, a discharge pipe, said cylinder being turnable about its axis from a position in which its port communicates with one pipe to a position in which its port communicates with the other pipe, a piston operating in said cylinder, an actuator connected to said piston and having a rack bar, and an operating pinion meshing with the rack bar, 70 movement of the rack bar given to it by the pinion operating both to reciprocate the piston and to move the cylinder from one position to the other.

5. In a measuring pump, the combination with a cylinder having a port, an inlet pipe, a discharge pipe, said cylinder being turnable about its axis from a position in which its port communicates with one pipe to a position in which its port communicates with the other pipe, a piston operating in said cylinder, a rectangular rack bar connected to the piston, and an operating pinion meshing with the rack bar, the movement of the rack bar operating both to reciprocate the piston 80 and to move the cylinder from one position to the other.

6. In a measuring pump, the combination with a casing having an inlet pipe and a discharge pipe, a cylinder within the casing and having a port, said cylinder being turnable about its axis to bring its port into register with either pipe, a piston in said cylinder, an operating pinion journaled in 95 bearings carried by the casing, and a rectangular rack bar meshing with the pinion and connected to the piston, the movement of the rack bar which is given to it by the pinion operating to reciprocate the piston and also to turn the cylinder to bring its port into 100 communication first with one pipe and then the other.

In testimony whereof, I have signed my name to this specification.
